OSCAR D. WILLIS AND LEO C. WITHROW, OF HUNTINGTON, WEST VIRGINIA.

COMBINATION FURNITURE.

Application filed May 25, 1923. Serial No. 641,470.

Our present invention has reference to an article of furniture, and our primary object is to produce an article of this character convertible into a folding library table, a dressing table and a writing desk.

The invention further resides in the novel construction, combination and operative association of parts such as is set forth in the following description and pointed out with 10 particularity in the appended claim.

With these and other objects in view, reference is to be had to the drawings which accompany and which form part of this application.

15 In the drawings:—

Figure 1 is a front elevation of the improvement employed as a library table.

Figure 2 is a top plan view thereof.

Figure 3 is a sectional view approximately 20 on the line 3—3 of Figure 2, showing the device when employed as a dressing table.

Figure 4 is a sectional view approximately on the line 4—4 of Figure 3, illustrating the device in the position disclosed in the said 25 Figure 3, but illustrating how the same may be also employed as a writing desk.

Figure 5 is an elevation showing the device in set-up position.

Figure 6 is a detail view of the pivoted 30 dogs embodied in the invention, and

Figure 7 is a view partly in elevation and partly in section of one of the swinging drawers embodied in the invention.

Our improved article of furniture includes a top 1 which is supported at its corners on legs 2. Below the top, the legs and if desired the said top have secured thereto rear, side and bottom members to provide compartments for slidable drawers 3 which 25 open from the front of the furniture and a central compartment 4 closed by a door 5. The door 5 is hinged to the lower wall of the floor 6 that provides the compartments, suitable means 7 being employed for normally latching the door 5 to the top 1.

The drawers 3 are comparatively shallow, that is, they do not extend the entire depth of the compartments in which they are received, while the rear of the compartment 4 50 is divided by partitions into pigeon holes 8. The side walls of the compartment 4, indicated for distinction by the numeral 9, have openings therethrough forward of the pigeon holes, and pivotally secured, as at 10 55 at the front or forward portion of the said openings there are swingable drawers 11.

These drawers have their outer walls rounded, being struck from the pivot 7 so that the same will readily swing into the compartments 12 to the rear of the drawers 3.

The door 5 is so hinged to the floor 6 as to permit of the same being swung there beneath, and when so positioned the said door is engaged by a catch 13.

The top 1, directly over the compartment 4 has a substantially rectangular opening therethrough designed to be closed by a frame 14 that is hinged, as at 15 to the rear wall provided in the top by said opening. Hingedly secured to the sides of the frame 70 14 there are smaller frames 16. These frames are foldable against the frame 14 and are of a width approximately half of that of the said frame 14. The frames 14 and 16 have mirrors therein.

The lower corners of the frame 14 are notched, and in these notches there are pivoted, as at 17, metal straps 18. Pivots secured to the straps 18, as at 19, there are links 20, the said links having their free ends pivotally supported, as at 21, to the outer sides of the walls 9. In the path of contacting engagement with the lower edges of each of the links 20 there is a pivotally mounted dog 22, each of which being supported upon a suitable bracket 23 secured to the said walls 9, and each of the dogs is influenced by a spring 24. When the mirror frame 14 is swung to vertical position the spring influenced dogs will be brought beneath the links 20 to effectively support the frame in such position. The side frames are, of course, swingable on the main frame 14 so that the mirrors in the several frames may be properly positioned with respect to the user 90 of the device when set up as a dressing table.

An outward pull on the dogs 22 will disengage them from the links 20 and permit the mirror frame 14 to be swung downwardly to cover the opening in the table top. Before this is done, the side mirror frames 16 are swung against the main frame 14, and suitable means 25 is preferably employed for latching the confronting ends of these side frames together. The main frame is of a greater length than the side frames, and when in closed position the main frame will rest on the walls 9 and likewise rest on the door 5 when the latter is swung to closed position.

It is thought that the foregoing description, when taken in connection with the

drawings will fully set forth the construction of the improvement. The device is used as a library table when the frames are folded on the top as above set forth. The device is employed as a dressing table when the mirrors are in upright position, and also when in this position the article is employed as a writing desk.

Having described the invention, we claim:

A hinge frame swingable from a horizontal to a vertical position, straps pivotally secured to the lower corners of the frame, a

link pivoted to each strap and pivotally supported below and at the rear of the frame, a pivotally supported dog arranged beneath each link and spring means influencing the dog for contacting engagement with the lower edge of the link when the frame is swung from horizontal to a vertical position, for sustaining the frame in such position.

In testimony whereof we affix our signatures.

OSCAR D. WILLIS.
LEO C. WITHROW.
